UNITED STATES PATENT OFFICE.

CARL THEODOR DÖRR, OF OHLIGS, GERMANY, ASSIGNOR TO FRIED. KRUPP, OF ESSEN, GERMANY.

ORDNANCE POWDER-BAG.

SPECIFICATION forming part of Letters Patent No. 707,401, dated August 19, 1902.

Application filed March 31, 1902. Serial No. 100,859. (No specimens.)

To all whom it may concern:

Be it known that I, CARL THEODOR DÖRR, doctor of philosophy, residing at Ohligs, Rhenish Prussia, Germany, have invented 5 certain new and useful Improvements in Ordnance Powder-Bags, of which the following is a specification.

The present invention relates to those powder-bags which easily burn and are completely 10 consumed in firing and aims to render possible the regulation of the inflammability and combustibility of these powder-bags.

According to this invention this object is attained by producing the fabric from which 15 the powder-bag is made from threads of smokeless powder and from ordinary textile threads, (not nitrated.) The threads of smokeless powder are produced in any desired manner— as, for example, from a collodium solution— 20 while for the other character of threads the purpose will be served by selecting silk. The fabric can be so constructed by way of example that the threads of smokeless powder shall constitute the warp of the fabric and the ordinary textile threads be used for the weft, or the reverse may be the case, or both the warp and weft or the warp alone or the weft 25 alone may be made up of both the smokeless powder threads and the ordinary textile threads alternated or intermingled with each 30 other. Obviously this method admits of any

desired varying of the proportions of the two kinds of threads, since it is practicable to alternate one, two, or even more of one kind of thread with only one of the other kind of thread 35 or otherwise use said threads in the proportion of one, two, or more of one kind to one of the other in the formation of the fabric.

A further regulation of the inflammability and combustibility of the powder-bag can be 40 attained by substituting for the simple textile thread such threads that have been saturated more or less with a solution of smokeless powder.

Having thus described the invention, the 45 following is what is claimed as new therein:

1. An ordnance powder-bag consisting of a fabric constructed of threads of smokeless powder, and of textile threads associated in proportions corresponding to inflammability 50 and combustibility desired.

2. An ordnance powder-bag consisting of a fabric produced from threads of smokeless powder, and of textile threads provided with a solution of smokeless powder. 55

In testimony whereof I have hereunto set my hand in the presence of two subscribing witnesses.

CARL THEODOR DÖRR.
